UNITED STATES PATENT OFFICE

114,247

DESIGN FOR AN AUTOMOBILE GRILLE PROTECTOR

Ralph N. Wiesenberger, Cleveland, Ohio, assignor to The Ward Products Corporation, Cleveland, Ohio

Application December 24, 1938, Serial No. 81,975

Term of patent 14 years

To all whom it may concern:

Be it known that I, Ralph N. Wiesenberger, a citizen of the United States, residing at Cleveland, in the county of Cuyahoga and State of Ohio, have invented a new, original, and ornamental Design for an Automobile Grille Protector, of which the following is a specification, reference being had to the accompanying drawing, forming part thereof.

In the drawing,

Fig. 1 is a front elevational view of an automobile grille protector showing my new design; and

Fig. 2 is a view taken upon line 2—2 of Fig. 1.

I claim:

The ornamental design for an automobile grille protector, as shown.

RALPH N. WIESENBERGER.
